CLAIM

The ornamental design for an actuator cap, as shown and described.

DESCRIPTION

In a preferred embodiment, the nature of this product is as an overcap for an aerosol container useful in connection with actuating such a container.

FIG. 1 is a top, right, front perspective view of an actuator cap embodying our new design;

FIG. 2 is a top plan view thereof;

FIG. 3 is a right side elevational view thereof, the left side elevational view being a mirror image of the right side shown;

FIG. 4 is a rear elevational view thereof; and,

FIG. 5 is a front elevational view thereof.
